CLAIM

The ornamental design for a monitor screen extender for laptop as shown and described.

DESCRIPTION

FIG. 1 is a front, right and top perspective view of a monitor screen extender for laptop, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is another front, right and top perspective view of the monitor screen extender for laptop in another state.

FIG. 11 is a rear perspective view of the monitor screen extender for laptop in a folded state.

FIG. 12 is a rear, right and top perspective view of the monitor screen extender for laptop in a state of use with the environment of a laptop.

FIG. 13 is an enlarged view of detail 13 in FIG. 2.

FIG. 14 is an enlarged view of detail 14 in FIG. 2; and, FIG. 15 is an enlarged view of detail 15 in FIG. 8.

The dot-dash broken lines in FIGS. 1, 2, 8, 9, and 13-15 depict the boundaries of the enlargements and form no part of the claimed design. The even-dash broken lines, showing the laptop in FIG. 12, represent unclaimed environment only and form no part of the claimed design. All other even-dash
